OF NEW YORK, N. Y., ASSIGNEES TO LION MATCH CO., INC., OF LONG ISLAND CITY,
NEW YORK, A CORPORATION OF NEW YORK.

MACHINE FOR SORTING AND STACKING BOOK MATCHES.

Application filed April 29, 1925. Serial No. 26,794.

This invention is a machine for sorting and stacking book matches; the object of the invention being, generally stated, to provide an apparatus which may be associated with 5 a match making machine in such manner as to receive book matches from such machine, and, after discarding the defective matches will stack the product of the match making machine and feed the stacked matches into 10 an accessible position for convenient manual removal from the machine, whereby the thus stacked matches can be readily packaged in suitable boxes for the trade.

It has heretofore been the practice to discharge the book matches directly from the machine in which they are made into a suitable container from which they are removed manually and after being manually stacked are placed in boxes for shipment, to the 20 trade. In order that book matches may be properly packaged, it is essential that they be placed alternately in opposite directions within the package, this being necessitated by the tapering contour of the book match.

25 Heretofore the alternate ranging of the book matches in proper stacks has been manually accomplished and has required considerable manual labor. In fact, three or four girls have usually been employed in the stacking of such matches and packaging 30 them in boxes. By the present invention, however, a large portion of this manual labor is accomplished mechanically, the matches being stacked alternately and in such relation that they may be picked up in bulk and deposited directly within the final packages.

35 Match making machines, as a general rule, produce a fairly uniform product, but experience has shown that a very small percentage of the product of such machines is defective in one way or another and should not be packaged with perfect matches for the trade. It has heretofore been the practice to accomplish this sorting manually. 40 The present invention, however, provides for the automatic sorting of defective matches, so that only the perfect product is stacked and placed in position to be packaged by the packers.

50 The invention embodies many novel features and advantages, fulfills a long-felt

want in the trade, and functions with absolute certainty and efficiency in the carrying out of its intended functions.

Features of the invention, other than those particularly specified, will be apparent from the hereinafter detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is a side elevation of apparatus embodying the present invention.

Figure 2 is a longitudinal section through the apparatus of Figure 1, this view being taken on the line 2-2 of Figure 4.

Figure 3 is a fragmental transverse section on the line 3-3 of Figure 2, showing certain parts in elevation in the interest of clearness.

Figure 4 is a section on the line 4-4 of Figure 1.

Figure 5 is a section on the line 5-5 of Figure 1, showing, in the interest of clearness, a fragment of a match making machine with which the apparatus of this invention is adapted for cooperation.

Figure 6 is a section on the line 6-6 of Figure 2; and,

Figures 7 and 8 are diagrammatic views illustrating the manner in which book matches are positioned in proper relation to one another, so that when subsequently stacked, they will be consecutively in reversed relation with respect to one another.

The apparatus of the present invention may be conveniently constructed to embody two side frames or castings 1 and 2 mounted in any suitable manner in spaced parallel relation to one another by spacers 3 and constituting, collectively, the frame of the machine.

Associated with the frame is a substantially horizontal feed table 4, which, as shown in Figure 5, is adapted to be mounted in substantially flush cooperative relation with the delivery table or conveyor 5 of the machine for making book matches, so that the book matches M made by the match mak-

ing machine are delivered into cooperative relation to the apparatus of this invention.

Mounted to travel along and above the upper surface of the feed table 4 is an endless conveyor, shown as embodying a sprocket chain 6 passed around sprockets 7 and 8, and these sprockets are mounted on parallel shafts 9 and 10, which are maintained in proper spaced relation by means of spacing bars 11. The sprocket 8 is positioned to overlie the discharge table 5 of the match making machine and pusher fingers 12 are mounted on the chain to project outwardly therefrom, so that as the chain is caused to travel the match books M which are successively moved into cooperative relation with the fingers 12, are engaged by said fingers and caused to traverse the feed table 4.

It may be here stated that the arms 11 are pivoted on the shaft 9 and that the shaft 10 is journalled in the free ends of said arms. This permits the free ends of the arms to be raised, when desired, for the purpose of moving the fingers 12 out of cooperation with the match books on the tables 5 and 4. Normally, however, the parts gravitate into engagement with the stop 13 (Figure 1) and with the conveyor chain in proper cooperative relation with the matches to be fed.

In practice, some imperfect match books are produced by every match making machine and it is, of course, desirable that these imperfect match books be discarded. The imperfections are usually found in improper folding of the cover of the book match or in improper centering of the match comb within the cover. An example of the former instance is shown at M' in Figure 5. Such matches should be removed prior to packaging of the matches, and, in accordance with this invention, they are removed prior to stacking by entirely automatic means positioned in the path of the matches over the feed table 4.

The sorting mechanism to which we have referred is shown best in Figures 1, 2 and 5, and as associated with an opening 14 in the feed table 4. The sorting mechanism comprises two arms 15, one end of each of which is secured to a pivot 16. Each arm is provided on its inner surface with a ledge 17, while the lateral edges of the arms rise above the ledges 17 and extend in rearward directions beyond the rear edges of the ledges.

The lower edges of the extended portions of the arms are curved as shown at 18. The arms are positioned a distance apart equal to substantially the width of a perfect book match with slight allowances for clearance and when such a match is moved by the conveyor over the table, it will simply move between the arms 15 and traverse the upper surface of the ledges 17, which support the match during its passage over the opening

14, the match thereupon continuing to traverse the table 4 in a direction to the right in Figures 2 and 5.

If, however, an imperfect match, such, for example, as the match M' of Figure 5, is moved along the table 4 that portion of the match which projects laterally beyond the predetermined proper dimensions of the book will engage with the curved surfaces 18 of one or both of the fingers 15 and, as a match continues to move under the impulse of a conveyor finger 12, such match will be forced beneath one or both of the fingers 15 with the result that said fingers will be elevated from the full line position of Figure 2 to the dotted line position thereof. By this operation, the ledges 17 will be lifted sufficiently to uncover the opening 14 in the table and the defective match will fall through such opening into the discard, as shown in heavy dotted lines in Figure 2.

After an imperfect match has been discarded in the manner described, the fingers 18 will immediately descend by gravity and will thus be automatically positioned to receive the next match book. To insure proper operation of this mechanism, as well as to further insure the proper feed of perfect matches throughout the entire length of their travel along the feed table 4, said feed table is preferably of the transverse section shown in Figure 6, in which a match book is shown in dotted lines. From this figure, it will be noted that the table is provided with a longitudinal trough 19 along which the matches are adapted to pass. The small central depression 20, in the base of this trough, provides sufficient clearance for the wire staples frequently employed in book match construction and also permits of proper clearance for the pusher fingers 12.

It will also be noted in Figures 2 and 6 that the lower reach of the chain 6 runs in a channeled guide 6^a which serves not only to guide the chain, but to preclude lifting of the matches from the table 4.

In the machine shown in the drawings, the match conveyor for moving the matches along the feed table operates at a constant speed and is synchronized with the operations of the delivery mechanism 5 of the associated match machine to insure the engagement of the fingers 12 with the matches at desired times, the book matches thereafter moving along the feed table 4 at a constant speed.

It will be noted in Figure 5 that the matches are delivered from the match making machine to the apparatus of this invention with all of the books positioned in the same manner upon the delivery means 5, and in match making machines, it is common practice to deliver all matches in the same manner. For stacking, however, it is essential that the matches be alternately reversed, since the tapering contour of the

match book precludes efficient stacking of packaging in any other manner.

When the apparatus of this invention receives matches from the match making machine, the conveyor transports these matches, without reversal thereof, along the table 4 and delivers them in this manner to suitable mechanism for effecting the reversal of alternate matches in order to enable efficient 10 stacking. Mechanism for reversing the matches may vary without departing from the spirit of the invention, but a very satisfactory and novel means for accomplishing this result is illustrated in the drawings and 15 shown best in Figures 2, 4, 7 and 8.

By reference to Figure 4, it will be noted that a shaft 21 extends transversely through the plane of the machine and is journaled in the frame elements 1 and 2. On this shaft is 20 mounted a hub 22 and on this hub is affixed two circular metallic disks 23, which are spaced apart, so that their adjacent faces are spaced apart a distance substantially equal to the width of a book match M. Arranged 25 about the margins of these two disks and on their adjacent faces are interiorly extending flanges 24, the corresponding flanges on both disks being of the same shape and complementarily positioned, so that each two corresponding flanges constitute in effect a pocket adapted to receive and house a book match. These pockets open to the outer periphery of the disks. The number of pockets which 30 are employed may be varied, but in the particular construction shown four are illustrated.

These four pockets are designated 25, 26, 35 25^a and 26^a. Pockets 25 and 25^a are of identical shape and the pockets 26 and 26^a are also of identical shape, although the pockets 25 and 25^a and 26 and 26^a are of pronouncedly different shape, for reasons which will presently become apparent. Both disks are mounted rigid with respect to one another. 40 and to the shaft 21 and on one end of the shaft 21 is affixed a pinion 27 which meshes with a gear 28 fixed on a shaft 29. The shaft 29 is journaled for rotation in the frame and also has affixed thereto the wheel 30 of a Geneva movement. The other element of the Geneva movement embodies a crank 31 carrying a pin 32 and which crank is mounted on a shaft 33 which extends transversely 45 through the frame and carries at its opposite end a sprocket 34 which constitutes the prime mover of the apparatus. The Geneva movement is clearly shown in Figure 1 and inasmuch as Geneva movements are well known to the art (we do not consider it necessary to describe it in detail, other than to say that the sprocket 34 is driven at a constant speed and serves through the Geneva movement to drive the shaft 29 intermittently. This shaft 29 serves through the gear 50 28 and the pinion 27 to effect the intermit-

tent rotation of the shaft 21 on which the pocket carrying disks are fixed. It will be noted from Figures 1 to 4 that the shaft 9 of the conveyor is driven from a shaft 33 by a gear 35 fixed on the shaft 9 and meshing 55 with a gear 36 fixed on the shaft 31.

All of these gears, as well as the Geneva movement are of such ratio and the pockets 25, 25^a and 26 and 26^a are so positioned and the pusher fingers 12 so located that, as a 60 pusher finger delivers a match from the end of the feed table, one of the pockets will be stationary and in a position to receive such match. In order that the principle of operation involved in the cooperation of the 65 match reversing mechanism and the match feeding mechanism may be fully understood, we will now describe the principle of operation with regard more particularly to the 70 diagrammatic illustrations of Figures 7 and 75 8 of the drawings.

In Figure 7, the parts are shown in the relationship which exists at the time when one of the pusher fingers 12 forces the match into the pocket 25. While the match is travelling along the top of the table 4, the pocketed rotor is turned into the position of Figure 7 to bring the forward end of the pocket 25 into alignment with the discharge 80 end of the table 4. As the match continues to move along the table, butt-end first, it is moved into the pocket 25 and when this end engages the base of the pocket, the curvature of the base permits the match to continue to travel and to assume a substantially upright 85 position shown in dotted lines in this figure. After the match has been thus deposited and the finger 12 passes on its way, the Geneva movement, which we have described, 90 imparts rotation to the pocketed rotor through an angle of 90 degrees to bring the next pocket 26^a into cooperative relation to the table 4. The next match is meanwhile 95 passing along the table 4 under the impulse of the next pusher finger, so that by the time the match arrives at the discharge end of the table 4, the pocket 26^a has been moved into the position shown in Figure 8. The match is moved by the finger 12 in this figure 100 into the pocket in the manner shown in full lines and is moved up the inclined base of the pocket until the head end of the match is disengaged from the table, whereupon 105 the match falls into the dotted-line position 110 of Figure 8.

It will be noted from what has been said that the feed of the match into the pocket 25 effects the reversal of the match, while the feed of the match into the pocket 26^a is effected without reversal. Thus, in Figure 8, 115 wherein two matches are shown in the respective pockets 25 and 26^a, it will be seen that these matches are in reversed relation to one another.

Continuing the operation of the machine,

the Geneva movement again shifts the pocketed rotor to bring the pocket 25^a into cooperative relation with the table 4, and the next match is introduced into this pocket in the same manner as the two previous matches were introduced into the pocket 25. A further operation of the pocketed rotor positions the pocket 26 in cooperative relation to the table and the operations which were described with reference to the pocket 26^a are repeated in this particular pocket. It will thus appear that through one complete rotation of the pocketed rotor, it is charged with matches which are alternately reversed.

It is of course essential that the matches, after being positioned in the pockets, are held against inadvertent release therefrom until it is desired to discharge them and in order that the mechanism for accomplishing this result may be clearly understood, attention is directed to Figures 2 and 4 of the drawings, and particularly the former figure. From this showing, it will be noted that the outer periphery of the pocketed rotor is surrounded for an appreciable portion of its extent by a guard or housing 37, one end of which is slotted, as shown at 38 to permit the pusher fingers 12 to pass therethrough. With the extreme forward end of the guard 37 cooperates a latch 39, pivoted at 40, in such manner that the latch will be lifted by a match during its passage into one of the pockets, but after the match has passed and is discharged into the pocket, the latch 39 will fall and function as a gate to close the passage through which the match has left the table.

It will further be noted from Figure 2 that to the under side of the table is secured a guard 41 which is bent downwardly to substantially conform to the shape of the pockets 25 and 25^a and is thereupon bent into substantially the arc of a circle to form a cam or eccentric 42 which is eccentrically positioned with reference to the axis of rotation of the pocketed rotor. The function of this guard and eccentric member will be apparent from Figure 2, and it will there be seen that, when the match is discharged into the pocket 25, for example, it will fall into engagement with the guard 41 and be precluded from entirely falling out of the open side of the pocket. The eccentric portion of the guard is, however, in practice, made resilient and as the matches are carried around and approach the point of discharge which will presently be described, the guard will bear against the matches and lightly force them against the outer guard 37, so that they are fed positively by pressure of the rear ends of the pockets into registration with the discharge outlet of the rotor.

In the construction shown in the drawings, the discharge outlet of the rotor is in the

form of a vertical passage 43 positioned at the bottom of the rotor. The walls of this passage are stationary with respect to the rotor and through the intermittent operation of said rotor, the matches are delivered in proper reversed relation to this discharge passage. By reference to Figures 2 and 4, however, it will be noted that near the top of the discharge passage are a pair of pivoted flaps 44, which, in practice, have springs 75 associated with their pivots, so as to normally hold the flaps in the horizontal position shown in Figure 4.

Thus, when one of the pockets of the rotor is brought into registration with the discharge passage 43, the match contained in such pocket will simply gravitate into a position wherein it will rest on the flaps 44. The match will remain in this position until it is forced through and beyond the flaps by pressure applied to the top of the match. This pressure is applied by means of a shoe 45 (see Figure 2) which is pivotally mounted on a slide 46. The slide is mounted for vertical sliding movement in guides 47 on the walls of the discharge passage and is connected to an operating arm 48 pivoted to the frame of the machine at 49. To the arm 49 is pivoted a yoke 50 which straddles the shaft 33 and is provided with a cam follower 51, operating in a cam track 52, formed in a cam 53 which is fixed on said shaft 33.

When it is borne in mind that the shaft 33 carries a prime mover 34, it will be apparent that the operations of the cam 53 will be thoroughly synchronized with the rest of the operative parts of the machine. The parts are, in practice, so arranged that at each period of dwell or rest of the rotor, the cam will function to depress the shoe 45, for it is immediately preceding this time that a match is deposited on the flaps 44 and the function of the shoe 45 is to force the match past the flaps and into a chute 54 associated with the lower end of the discharge passage 43.

This chute or guide passage 54 is best shown in Figure 3. Here it is illustrated as connected to the lower end of the discharge passage 43 and as extending first in a downward and thereafter in an upward direction to the ultimate point of discharge atop a packer's table 55.

The advantage of this arrangement is that, after the machine has been operating for a short time, the entire length of the guide will be filled with matches, as shown in Figure 3, which matches will be under more or less pressure. The natural resiliency of the book match will allow it to be compressed to an appreciable extent, so that there is no possibility of sufficient pressure being generated at this point to cause clogging of the machine. It is desirable, however, that the matches be sufficiently close together as to

require the shoe 45 to actually force a match book past the flaps and to, by this action, advance all of the match books which have preceded it. That is to say, the feed of the 5 stacked matches through the chute is effected by the pressure of the shoe 45.

This arrangement insures close stacking of the matches in proper relation to one another and in a condition wherein they may be 10 readily picked up by a packer and lifted into the boxes during preparation of the matches for shipment. In order to permit ready access of the matches, the top of the chute or guide is cut away, as shown at 56, at its discharge end and through this opening, the operator inserts his hand to remove a stack of many matches at a time.

It is to be noted that by the arrangement which we have described, the matches are 20 delivered to the chute 54 in alternate reversed relation, so that they are delivered to the packer in the exact manner in which they must be placed in the boxes. This arrangement entirely eliminates the manual reversal 25 of alternate packages as has heretofore been required in this art.

The operation of the machine as thus far described will be apparent, but may be briefly summarized as follows.

30 Matches are fed by the match making machine into cooperative relation with the conveyor 6. The pusher fingers 12 transport the matches one at a time to the sorting mechanism at which point defective or imperfect matches are automatically discarded. The perfect matches pass uninterruptedly through the sorting mechanism and are fed to the pocketed rotor and during their entrance into the rotor, the alternate matches 35 are reversed. From the rotor, the matches are delivered into a chute which leads to a packing table, and this chute is so shaped as to maintain a column or stack of matches at all times, said stack being advanced intermittently by mechanical means which assures slight pressure of the stack desirable to maintain the matches in proper relation.

Finally the matches are delivered into accessible position to the packer in the exact 50 positions and relationship which they should occupy to facilitate manual packing.

The mechanism is simple, entirely positive and automatic in its operations, and may be attended by one operator. This is in 55 pronounced contradistinction to prior practice wherein the output of each match making machine provides labor for several persons in properly assembling the matches, alternately reversing them, sorting out the imperfect matches and packing the finished product in containers for shipment. The invention, therefore, not only greatly expedites work of packaging matches, but materially reduces the cost incident thereto.

60 The accompanying drawings show the in-

vention in its preferred practical form, but inasmuch as mechanical details may be modified without departing from the spirit of the invention, this invention is to be understood as fully commensurate with the appended 70 claims.

Having thus fully described the invention, what we claim as new and desire to secure by Letters Patent is:

1. Mechanism of the character described 75 embodying means for feeding a succession of match books along a predetermined path to a point of discharge, a movable member operable at the point of discharge and embodying a plurality of pockets adapted to be 80 brought, by movement of said member, successively into positions to receive match books at said point of discharge, alternate pockets being shaped to receive the match books with and without reversal of said 85 books, and a collection passage into which said member is adapted to subsequently discharge the matches in succession in the form of a stack in which alternate matches are reversed.

2. Mechanism of the character described 90 embodying a guide, a rotary member positioned at the discharge end of the guide and provided with a plurality of match receiving 95 pockets, means for intermittently rotating said member to successively bring the pockets into cooperative relation with the guide, means for moving match books along the guide continuously and with all the match books facing in the same direction, to 100 successively discharge the books into the pockets of the rotary member, the alternate pockets of the rotary member being shaped to effect automatic reversal of the match books discharged thereinto, a stack forming 105 guide, with the receiving end of which, the pockets of the rotary member are adapted to be successively brought into register, and means for precluding inadvertent disengagement of the match books from the rotary 110 member until said books are in alignment with the stack forming guide.

3. Mechanism of the character described 115 embodying a guide, a rotary member positioned at the discharge end of the guide and provided with a plurality of match receiving 120 pockets, means for intermittently rotating said member to successively bring the pockets into cooperative relation with the guide, means for moving match books along the guide continuously and with all the match books facing in the same direction, to successively discharge the books into the pockets of the rotary member, the alternate pockets of the rotary member being shaped to effect 125 automatic reversal of the match books discharged thereinto, a stack forming guide, with the receiving end of which, the pockets of the rotary member are adapted to be successively brought into register, means for 130

precluding inadvertent disengagement of the match books from the rotary member until said books are in alinement with the stack forming guide, and means for forcibly ejecting the match books from the pockets and into cooperation with the stack forming guide.

4. Mechanism of the character described embodying means for feeding a plurality of match books in succession with all of the match books facing in the same direction, a rotary member mounted to turn on a fixed axis and provided with a succession of relatively stationary seats adapted to be successively brought into cooperation with the match book feeding means as said member is rotated, alternate seats being shaped to automatically effect reversal of the match books received by said seats, stack forming means, and means for precluding inadvertent disengagement of the matches from their seats until the matches are brought, by rotation of said member, into cooperative relation to the stack forming means.

25 5. Mechanism of the character described embodying a rotary member, on which is rigidly formed a succession of match receiving pockets, all of said pockets being rigid with respect to one another; means for feeding match books to the pockets in succession with all of the match books facing in the same direction, certain of said pockets being shaped to receive the books without reversal and other pockets being shaped to automatically effect reversal of the match books when said books are introduced into the pockets.

40 6. Mechanism of the character described embodying a match guide, an endless conveyor cooperating with said guide and adapted to move a plurality of matches in succession along the guide and to discharge said matches from the guide with all of the matches facing in the same direction, a pocketed rotor mounted to receive the matches discharged from the guide and alternate pockets of which rotor are shaped to reverse the match books delivered thereto while the intermediate pockets are shaped to receive the match books without reversal, means for intermittently rotating the rotor to successively bring the pockets thereof into cooperative relation with the discharge end of the guide, a stack forming guide, means for precluding inadvertent release of the match books from the pockets until said books are juxtaposed with the stack forming guide, and means for forcibly ejecting the matches from the pockets and into the stack forming guide when said match books are in a position for such movement.

65 7. Mechanism of the character described embodying a match reversing device having a plurality of relatively immovable pockets into which match books, all facing in the

same direction, are adapted to be successively fed, and means to move the reversing device to bring said pockets successively into position to receive the match books, certain of said pockets being shaped to effect automatic reversal of the books upon introduction of such books into said pockets and other pockets being shaped to receive the books without reversal.

8. Mechanism of the character described embodying a match reversing device having a plurality of relatively immovable pockets into which match books, all facing in the same direction, are adapted to be successively fed, and means to move the reversing device to bring said pockets successively into position to receive the match books, every second pocket being shaped to effect automatic reversal of the books upon introduction of such books into said pockets and the intermediate pockets being shaped to receive the books without reversal.

9. Mechanism of the character described embodying a movable match reversing device having a plurality of relatively immovable holders adapted to receive match books individually with all the books facing in the same direction, and means to intermittently move said member with intermediate periods of dwell to permit the books to be introduced into the holders, certain of said holders being shaped to effect automatic reversal of the match books upon entry of the books into said holders and during said periods of dwell, and other holders being shaped to receive books without reversal.

10. Mechanism of the character described embodying a movable match reversing device having a plurality of relatively immovable holders, adapted to receive match books individually at a receiving point with all the books facing in the same direction, and move them to a point of discharge, ejector means at such point of discharge, means to move said reversing device apast the receiving and discharge points to bring the holders successively into position to receive the match books and to thereafter convey the books to the point of discharge, certain of said holders being shaped to effect automatic reversal of the match books upon receipt of such books, and other holders being shaped to receive match books without reversal; and means to maintain the books in the holders and guide them into cooperative relation with the ejector means at the discharge point.

11. Mechanism of the character described embodying a rotatable match reversing device having a succession of annularly disposed relatively immovable pockets adapted to receive match books individually at a receiving point, with all of the books facing in the same direction and to move them to a point of discharge, ejector means at such

point of discharge, means to intermittently rotate said device with intermediate periods of dwell to permit the books to be introduced into the pockets and to convey them to the point of discharge, every second pocket presented at the receiving point being shaped to effect automatic reversal of the book matches upon the entry of the books into said pockets and during said periods of dwell, and the intermediate pockets being shaped to receive books without reversal, and a stationary guiding element to maintain the books in the pockets, while they are being conveyed to the point of discharge and for guiding said books during such movement into cooperative relation with the ejector means at the discharge point.

12. Mechanism of the character described embodying a match reversing device comprising spaced apart disks mounted to rotate on a common axis and collectively carrying match receiving pockets adapted to receive book matches individually, certain of said pockets being shaped to effect automatic reversal of the match books upon entry into the pockets and other pockets being shaped to receive the books without reversal.

13. Mechanism of the character described embodying a match reversing device comprising spaced apart disks mounted to rotate on a common axis and collectively carrying match receiving pockets adapted to receive book matches individually, certain of said pockets being shaped to effect automatic reversal of the match books upon entry into the pockets and other pockets being shaped to receive the books without reversal, and match book guiding means positioned in the space between said disks and adapted to engage with those portions of the match books which bridge said space.

14. Mechanism of the character described embodying a match reversing device comprising spaced apart disks mounted to rotate on a common axis and collectively carrying match receiving pockets adapted to receive book matches individually, certain of said pockets being shaped to effect automatic reversal of the match books upon entry into the pockets and other pockets being shaped to receive the books without reversal, a guide member positioned peripherally of the pockets to preclude match books from falling out of the pockets, and another guide member positioned in the space between the disks and adapted to engage with those portions of the match books which bridge said space, said guides cooperating to guide the match books into predetermined position at a discharge point.

15. Mechanism of the character described embodying spaced apart disks mounted to rotate on a common axis and collectively carrying marginally disposed pockets, the open sides of which are at the peripheries of

the disks, certain of said pockets being shaped to effect automatic reversal of match books introduced into the pockets while the disks are stationary.

16. Mechanism of the character described embodying spaced apart disks mounted to rotate on a common axis and collectively carrying marginally disposed pockets, the open sides of which are at the peripheries of the disks, certain of said pockets being shaped to effect automatic reversal of match books introduced into the pockets while the disks are stationary, guide means arranged peripherally of the disks to preclude the match books from falling out of the pockets, and guide means positioned in the space between the disks and adapted to engage with those portions of the match books which bridge such space, both of said guiding means cooperating with one another to guide the match books to a predetermined point of discharge.

17. Mechanism of the character described embodying spaced apart disks mounted to rotate on a common axis and collectively carrying marginally disposed pockets, the open sides of which are at the peripheries of the disks, certain of said pockets being shaped to effect automatic reversal of match books introduced into the pockets while the disks are stationary, guide means arranged peripherally of the disks to preclude the match books from falling out of the pockets, guide means positioned in the space between the disks and adapted to engage with those portions of the match books which bridge such space, both of said guiding means cooperating with one another to guide the match books to a predetermined point of discharge, and ejector means operating at the point of discharge for removing the books from the pockets.

18. In mechanism for handling book matches, the combination of means for continuously moving a plurality of book matches along a predetermined path with all the match books facing in the same direction, match book reversing means positioned to receive said matches at the delivery terminus of said path, and sorting means in the path of said match books to divert improperly folded match books from the reversing means.

19. In mechanism for handling book matches, the combination of match book sorting means, match book reversing means, and means for feeding match books from the sorting means to the reversing means.

20. In mechanism for handling book matches, the combination of match book sorting means, match book reversing means, means for feeding match books from the sorting means to the reversing means, and stacking means positioned to receive the match books from the reversing means.

21. In mechanism for handling book matches, the combination of match book reversing means, conveying means for moving match books to the reversing means with all 5 the books facing in the same direction, and sorting means in the path of the match books to divert improperly folded match books from the passage to the reversing means.

10 22. In mechanism for handling book

matches, the combination of match book sorting means, match book reversing means, and means for feeding the folded match books to assorting means and from the assorting means to the reversing means. 15

In testimony whereof we have signed the foregoing specification.

ANDREW SHMYROFF.
BORIS BOGOSLOWSKY.
